UNITED STATES PATENT OFFICE.

HAROLD P. BROWN, OF CHICAGO, ILLINOIS.

ELECTRO-MAGNET.

SPECIFICATION forming part of Letters Patent No. 330,463, dated November 17, 1885.

Application filed March 14, 1885. Serial No. 158,746. (No model.)

To all whom it may concern:

Be it known that I, HAROLD P. BROWN, a citizen of the United States, residing at Chicago, in the county of Cook and State of Illinois, have invented a new and useful Improvement in Electro-Magnets, of which the following is a specification.

In rheostats for regulating electric-light and other apparatus where strong currents are required difficulty has been experienced in using the ordinary metal-surface contacts, owing to the same becoming blackened or the surface becoming oxidized or deteriorated by the sparks or heat generated in making and breaking contacts, and though mercurial contacts have heretofore been used their use has been very dangerous with strong currents, owing to the oxidation of the mercury and to the poisonous fumes generated by the sparks or heat in making and breaking contacts. In the rheostats heretofore in use great difficulty has been experienced in keeping the spring attached to the armature-lever in proper adjustment to balance the force of the electro-magnet. The force of a coiled spring increases as it is compressed in the same ratio inversely as the square of the distance, as the force of the magnet increases as the armature approaches its core. Still the force of the spring is subject to so many variations from changes in temperature and other causes that the spring cannot be relied upon to act with certainty where nice adjustments are required. I overcome these and other objections by the present improvements, which consist in making and breaking contact through a cup of mercury, which is covered with a hydrocarbon oil or other liquid to prevent any fumes of mercury from being generated or escaping, or any oxidization of the mercury, and in balancing the force of the electro-magnet by means of a weight suspended from two divergent points, so that the retractile force of the weight on the armature-lever will increase in the same ratio as the force of the magnet increases as its armature-lever is drawn up. To diminish the friction of the armature-lever I mount it pivotally by means of a flat flexible spring, instead of by the usual pivot or hinged joint.

In the accompanying drawings, Figure 1 is

a side elevation of a device embodying my invention. Fig. 2 is a plan view; Fig. 3, a section on line 3 3 of Fig. 2, through the mercury-cup; and Fig. 4 is an end view of the adjusting-screw by which the force of the suspended weight is regulated. Fig. 5 shows an improved form of the mercury-cup, having an enlargement at the surface of the mercury 55 so that the expansion of the mercury 60 will not materially affect its height.

In said drawings, A represents an electro-magnet; A', its core. The coil of this magnet may be included in any circuit which governs the opening and closing of another circuit. 65

B is the armature-lever, and C C' the circuit-wires between which contact is to be made and broken, one being connected to the armature-lever B and the other to the mercury-cup D. The circuit C C' is or may be any 70 circuit which is desired to be closed and broken by variations in the current on the circuit in which the coil of the magnet A is included. The mercury-cup D is only partially filled with mercury d, and its surface is then covered with some liquid, d', preferably a hydrocarbon oil, to prevent the generation or escape of any poisonous fumes from the mercury. If a hydrocarbon oil is used for this liquid, no fumes will be generated, as such liquid contains no oxygen. Water, however, 75 may be used with success, but it is liable to evaporation and other objections. The contact-piece b is provided with screw-threads, so that it may be adjusted in the arm b', which 80 is secured to the armature-lever B. The armature-lever B is mounted movably on the base-block a by means of a flat flexible spring, b'', one end of which is secured to said base-block and the other end to said armature-lever. The 85 armature B' is provided with screw-threads, so that it may be adjusted on the armature-lever.

E is a weight suspended by the cord e, one end of which is attached to a hook, e', on the 90 armature-lever, near its outer or upper end, and the other end is wound around the adjusting-screw E', which is mounted on the part E'', and preferably at about the same level as the hook e'. By turning the adjusting-screw E' the 95 cord or line from which the weight is suspended will be shortened and the retractile force of the

weight on the armature-lever correspondingly increased. As the armature-lever is drawn up by the force of the magnet the distance between the points e' and E' , between which the weight is suspended, is of course increased, so that the weight-cord will approach nearer a straight line or a horizontal position, and the retractile force of the weight on the armature-lever will be increased in practically the same ratio as the force of the magnet is increased by the movement of the armature. The line e should be made of strong cord or wire, so that its length will not increase by tension of the weight. I prefer to use a cord, but any other flexible or jointed connection may be employed. By using a cord its length may be very conveniently adjusted by simply winding it around the adjusting-screw E' .
 E^3 is a set-screw by which the adjusting-screw E' may be fixed in position after the apparatus is properly adjusted. The motion of the armature-lever is limited by the adjusting-screws b^3 b^4 , and the line e may be connected directly to the armature of the magnet, or, in case of a solenoid, to its movable core, instead of to a lever or other device operated by such movable core or armature, if desired. I have, however, shown in the drawings what I deem to be the best means of practicing my invention.

The mercury-cup may be made of any suit-

able material. If it is made of metal, the wire C' may be connected to the cup, but if made of glass the wire C' will of course be connected with the mercury in the cup. 35

I claim—

1. The combination, with electro-magnet A and its movable armature-lever B, of a weight suspended from said armature-lever and from another divergent or distant point, 40 substantially as specified.

2. The means of balancing the force of an electro-magnet, consisting of a weighted line connected at one end with the movable armature or core of said magnet, and at its other 45 end to a distant support, so that the movement of the armature or core of the magnet will vary the retractile force of said weighted line, substantially as specified.

3. The combination of electro-magnet A, 50 armature-lever B, suspended weight E, cord e, and adjusting-screw E', substantially as specified.

4. The combination of electro-magnet A, armature-lever B, suspended weight E, cord 55 e, adjusting-screw E', and set-screw E³, substantially as specified.
